HIGH SPEED RELAY

Anthony E. Sprando, Portland, Oreg., assignor to Iron Fireman Manufacturing Company, Portland, Oreg.

Application September 27, 1956, Serial No. 612,495

8 Claims. (Cl. 200—87)

This invention relates generally to electric relay mechanisms and more particularly to sensitive millisecond relays required to withstand mechanical or thermal shock or a wide range of mechanical vibration without loss of calibration or operating reliability.

It is a principal object of this invention to provide such a relay having no organic structural parts to vary in size, shape or position under thermal or mechanical shock or vibration.

It is a second object of this invention to provide such a relay designed to require no organic structural parts.

How these and other objects are attained is explained in the following description referring to the attached drawing in which

Fig. 1 is a side elevation view in partial section of a relay with a single pole switch, the relay being made in accordance with the teaching of this invention and being encapsulated in a standard form of hermetically sealed container having the electric terminals for the relay insulatedly sealed through the end of the container in a well known standard pattern.

Fig. 2 is a view similar to Fig. 1 but with an additional relay encapsulated within the same container.

Fig. 3 is a view in plan section along the line 3—3 of Fig. 1.

Fig. 4 is a fragmentary view in side elevation and partial section as viewed from the line 4—4 in Fig. 2.

Fig. 5 is a view in plan section along the line 5—5 of Fig. 4.

Like reference numerals refer to like parts in the several figures of the drawing.

Referring now to the drawing at 11 is shown a container base rabbeted at 12 to be received in the open end of container cup 13 to which base 11 is soldered in final assembly.

As shown in Figures 4 and 5 there are ten spaced electric terminals, 14 to 23, hermetically and insulatedly sealed with glass 24 into appropriate holes 25 in base 11. Metal axle 26 fixed axially to base 11 is formed with a longitudinal rib, not shown, to require proper registration, in use, of terminals 14, 23 in a plug receptacle, not shown, common in the art. Fixed upwardly axially on base 11 is a stud 27 having its upper end threaded, as shown. Toroidal ceramic insulator 28 cored centrally to receive stud 27 has an upwardly extending neck, not shown, received by a mating centrally bored hole, not shown, in electromagnet base part 29. Insulating washer 30 resting on base part 29 together with lock washer 31, nut 32 and ceramic insulator 28 insulatedly secure magnetic circuit base part 29 to container base 11.

As particularly shown in Figures 3 and 4 relay frame 33 is shown to comprise an annular ring 34 flattened on opposite sides as at 35 and rabbeted at 36 to enter cap 37 to which ring 34 is soldered in assembly. Insulatedly and hermetically sealed within annular ring 34 by a filling of inorganic glass material 38 are magnetic circuit pole pieces 39, 40, and electrical bushings 41 to 44 internally threaded to receive screws 45 to 48 for the purpose of securing stationary contact brackets 49, 50 in place as shown.

As shown particularly in Figure 4 for pole piece 40, electromagnetic coils 51 and 52 are placed axially over pole pieces 39, 40 after which magnetic circuit base 29

2

is riveted onto pole pieces 39, 40, all before magnetic base 29 is fixed to container base 11 by stud 27 and nut 32.

The upper or free ends of both pole pieces 39, 40 have half round sections removed leaving diametral flat surfaces in the same plane on both pole pieces. Reed armature 53 has one end positioned as shown and welded to the flat surface of pole piece 40 after which segment 54 of pole piece 40 is replaced as shown and welded to reed 53 and pole piece 40. Normally the other end of reed 53 would lay adjacent the flat surface of pole piece 39.

The relay magnetic circuit is seen to include magnetic base part 29, pole pieces 39, 40 and reed 53, all of magnetic material. The magnetic circuit is arranged to be energized when an electric current is passed through coils 51, 52 connected so that the magnetomotive forces of the two coils are additive in setting up the magnetic field in the magnetic circuit. Two ends of the coils 51 and 52, not shown, are connected together while as shown in Fig. 1 the other two ends of coils 51 and 52 are connected to relay terminals 16 and 15. The magnetic circuit parts are not electrically insulated one from the other so that by connecting base part 29 to terminal 18 as shown, terminal 18 is electrically connected to reed 53 and the relay switch moving contact 55 carried by reed 53 as shown in Figure 3.

Stationary contacts 56 and 57 of resilient non-magnetic electrically conducting material are seen in Fig. 3 to be welded at one end respectively to contact brackets 49 and 50. Contact bracket 49 insulatedly supported by screws 45, 46, set into bushings 41, 42 in glass 38, sealed into ring 34 of relay frame 33 is shown to be connected through bushing 42 to relay terminal 22. Contact bracket 50 insulatedly supported by screws 47, 48 set into bushings 43, 44, in glass 38, sealed into ring 34 of relay frame 33 is indicated to be connected through bushing 44, not shown, to relay terminal 17.

It is seen that of the ten relay terminals 14 to 23 set into container base 11 five are required when a single relay only is encapsulated in the container as shown in Fig. 1 of the five terminals used, 15 and 16 feed current to the operating coils 51, 52, 18 connects to the moving contact of the S. P. D. T. relay switch and 17 and 22 connect to the two stationary contacts of the relay switch. Thus five terminals are needed for one relay and the additional 45 five are available when an additional relay is encapsulated in the same container as shown in scheme in Fig. 2. It will be noticed in Figure 2 that the flattened edges 35 of rings 34 allow clearance from the inside of container cup 13 for the wires, not shown, from the upper end of the can to be brought down to the terminal end of cup 13 to connect the second relay with the relay terminal. The particular terminals used for a particular purpose is a matter decided by the use to which the relay is put.

When a single relay is used it is ordinarily tightly supported in container 11, 13 as shown in Figure 1 by use of the cylindrical spacer 58 and the annularly rippled spring washer 59. When two relays are encapsulated in the same container 11, 13, switch cap 37 is not used the relays are turned switch end to switch end as shown in Figure 2 and securely relatively positioned by entering the rabbeted surfaces 36 of the respective relay base rings 34 into the opposite ends of spacer 58. Ceramic insulating disk 60 is then used between the upper relay parts and the spring washer 59.

To return to the construction of the relay switch, it is seen in Figure 3 that opposing spring leaves 61, 62 have adjacent ends welded respectively to opposite sides of magnetic pole piece 49, 54. The free ends of leaves 61, 62 are oppositely resiliently biased against the opposite sides of reed 53. Screws 63, 64, threadedly engaged through contact brackets 50, 49 respectively are respectively adjustable to contact leaves 61, 62 with pressures determined

for two distinct purposes. One purpose is to position the free end of reed 53 away from pole piece 39 when coils 51, 52 are unenergized so that moving contact 55 will be in contact with stationary contact 56. The other important purpose is to adjust the biasing forces of leaves 61, 62 on reed 53 to resist the motion of reed 53 by the minute rubbing of leaves 61, 62 on reed 53 when reed 53 moves to shift movable contact 55 from one stationary contact 56 or 57 to the other.

It should also be noticed that screws 65, 66 threadedly engaged through contact brackets 50, 49 respectively are respectively adjustable to position resilient stationary contacts 57, 56 with respect to moving contact 55 in the respective two positions reed 53 will take when coils 51, 52 are energized or unenergized. The teetering support of resilient contacts 57, 56 between the ends thereof by screws 65, 66 is effective in preventing contact bounce of moving contact 55 on striking either of the stationary contacts since on the attempt to bounce off the contact 55 supported on reed 53 the energy of the reed is first absorbed by the yielding stationary contact less the frictional energy absorption of the friction leaves 61, 62 and then the remaining energy is returned to the reed 53 by the stationary contact against the friction energy absorption of leaves 61, 62. While the motions and energies are small the result of the combination of the reed with its biasing leaves and the resilient stationary contacts is to produce a relay switch with substantially no contact bounce.

It of course should be pointed out as a requirement of the disclosed rigid frame structure having no organic insulating parts that each of the screws 63, 64, 65 and 66 are tipped with Pyrex glass on their inner ends so that no wear or change of calibration will be caused by the slight rubbing when the reed structure is in motion of contacts 57, 56 on screws 65, 66 or of leaves 61, 62 on screws 63, 64. The glass tips of screws 63, 64 also electrically insulate the vibrating reed structure from a respective stationary contact structure when the reed structure is in contact with the other stationary contact structure through the moving contact 55.

Having recited some of the objects of this invention and disclosed and described a preferred form in which the invention may be practiced, the use, construction, adjustment and operation of the invention will be apparent to those skilled in the art.

I claim:

1. A mechanically stable high speed relay comprising an inorganic electrically insulating mechanically rigid base disk, a pair of spaced parallel magnetic pole pieces hermetically sealed in said base to extend from both sides thereof, a magnetic yoke connecting the ends of said pole pieces on one side of said disk, a magnetic resilient reed having one end fixed to the other end of one of said pole pieces on the other side of said disk, the free end of said reed, extending towards the other end of the other of said pole pieces on said other side of said disk to terminate there-alongside, a second resilient reed having one end fixed to said other end of said one of said pole pieces laterally spaced from said one end of said magnetic reed, the free end of said second resilient reed being biased against said free end of said magnetic reed to bias the free end of said magnetic reed away from said other end of said other of said pole pieces, and an electromagnetic coil surrounding part of the series magnetic circuit formed by said yoke, said pole pieces and said magnetic reed, said coil being adapted when energized to energize said series magnetic circuit to cause the free end of said magnetic reed to move against the bias of said second reed towards said other end of said other of said pole pieces.

2. The mechanically stable high speed relay of claim 1 including a third resilient reed having one end fixed to said other end of said one of said pole pieces laterally spaced from said one end of said magnetic reed on the other side thereof from said one end of said second resilient reed, the free end of said third resilient reed being biased against

said free end of said magnetic reed in opposition to the free end of said second magnetic reed.

3. The mechanically stable high speed relay of claim 2 including a movable contact moved by the free end of said magnetic reed as said magnetic reed is moved, a stationary contact structure insulatedly sealed in said base to extend therefrom on the said other side thereof, said first stationary contact structure including a first stationary contact positioned to be contacted by said movable contact when said coil is deenergized and the free end of said magnetic reed is moved away from said other end of said other of said pole pieces by said first resilient reed.

4. The mechanically stable high speed relay of claim 3 including a second stationary contact structure insulatedly sealed in said base to extend therefrom on the said other side thereof spaced from said first stationary contact structure on the other side of said reeds therefrom, said second stationary contact structure including a second stationary contact positioned in opposition to said first stationary contact to be contacted by said movable contact when said coil is energized and the free end of said magnetic reed is moved by the energy of said magnetic circuit towards said other end of said other of said pole pieces against the bias of said first resilient reed.

5. The mechanically stable relay of claim 3 in which said first stationary contact includes a first resilient part secured at one end to said first stationary contact structure with the other end of said first resilient part biased away from said movable contact and said first stationary contact structure includes a first adjustable means positioned to contact said first resilient part between the ends thereof adjustably, rockably and resiliently to position the free end of said first stationary contact with respect to said movable contact.

6. The mechanically stable relay of claim 4 in which said second stationary contact includes a second resilient part secured at one end to said second stationary contact structure with the other end of said second resilient part biased away from said movable contact and said second stationary contact structure includes a second adjustable means positioned to contact said second resilient part between the ends thereof adjustably, rockably and resiliently to position the free end of said second stationary contact with respect to said movable contact.

7. The mechanically stable relay of claim 3 in which said first stationary contact structure includes a third adjustable means positioned to contact said second resilient reed adjustably, rockably and resiliently to position the free end of said magnetic reed by said second resilient reed.

8. The mechanically stable relay of claim 4 in which said second stationary contact structure includes a fourth adjustable means positioned to contact said third resilient reed adjustably, rockably and resiliently to position the free end of said magnetic reed by said third resilient reed.
